(57) **CLAIM**

The ornamental design for an illuminated dental accessory for holding saliva ejection tube, as shown and described.

DESCRIPTION

FIG. 1 is a front perspective view of an illuminated dental accessory for holding saliva ejection tube according to a first embodiment of my design;

FIG. 2 is a front elevational view thereof;

FIG. 3 is a rear elevational view thereof;

FIG. 4 is a top elevational view thereof;

FIG. 5 is a bottom elevational view thereof;

FIG. 6 is a first side elevational view thereof;

FIG. 7 is a second side elevational view thereof;

FIG. 8 is a front perspective view of an illuminated dental accessory for holding saliva ejection tube according to a second embodiment of my design;

FIG. 9 is a front elevational view thereof;

FIG. 10 is a rear elevational view thereof;

FIG. 11 is a top elevational view thereof;

FIG. 12 is a bottom elevational view thereof;

FIG. 13 is a first side elevational view thereof; and,

FIG. 14 is a second side elevational view thereof.

The broken line showing of various features is for the purpose of illustrating unclaimed portions of the illuminated dental accessory for holding saliva ejection tube and forms no part of the claimed design.
